United States Patent Office

Des. 191,046
Patented Aug. 8, 1961

191,046

CAN OPENER

James L. Hvale, Chicago, Ill., assignor to Ekco Products Company, Chicago, Ill., a corporation of Delaware

Filed Aug. 23, 1960, Ser. No. 61,863

Term of patent 14 years

(Cl. D22—2)

FIG. 1 is a side elevational view of a can opener showing my new design.

FIG. 2 is a similar view showing the article as it appears from the side reverse to that shown in FIG. 1.

FIG. 3 is a top plan view thereof.

FIG. 4 is a front end elevational view thereof.

I claim:

The ornamental design for a can opener, as shown.
